UNITED STATES PATENT OFFICE.

JOHN REECE, OF BOSTON, MASSACHUSETTS.

BUTTON-HOLE-BARRING MACHINE.

SPECIFICATION forming part of Letters Patent No. 349,358, dated September 21, 1886.

Application filed April 28, 1884. Serial No. 129,532. (No model.)

To all whom it may concern:

Be it known that I, JOHN REECE, of Boston, county of Suffolk, and State of Massachusetts, have invented an Improvement in Button-Hole-Barring Machines, of which the following description, in connection with the accompanying drawings, is a specification, like letters on the drawings representing like parts.

This invention has for its object the production of a machine more especially adapted to bar the square end of an eyelet-ended button-hole previously finished about its sides and eyelet on a button-hole sewing-machine. To accomplish this object I have provided an ordinary sewing-machine, it being herein shown as a "Singer," with an attachment adapted to operate a combined pressing and feeding foot, which forms a part of the said attachment, the usual presser-foot of the sewing-machine being dispensed with. The attachment contains two disks or pattern-plates which rotate once while finishing each button-hole, and determine the number of stitches made in the production of the bar which finishes the square end of the button-hole, a depression in the face of one of the disks automatically stopping the machine when the said bar has been completed. The said attachment also contains a cam by which to move the presser and feeding foot with the fabric or material at right angles to the button-hole slit, so as to make preferably three stitches to constitute the body for the bar, and it contains a second cam to move the said pressing and feeding foot and fabric or material longitudinally with relation to the button-hole slit, to thereby stitch backward and forward over the said body.

My invention consists in an attachment, substantially such as hereinafter described, and in mechanical details to be set forth in the claims at the end of this specification.

Figure 1 represents in side elevation, but partially broken out, a Singer sewing-machine having applied to it my improvements; Fig. 2, a detail of the automatic tension mechanism; Fig. 3, a top or plan view of the attachment applied to the bed of a Singer machine, the frame-work being partially broken away; Fig. 4, an under side view of a sufficient portion of a sewing-machine to illustrate one form of mechanical devices to operate the attach-

ment. Fig. 5 is a section of Fig. 4 on the line $x\bar{x}$; Fig. 6, a section of Fig. 3 on the line $x^2\bar{x}^2$; Fig. 7 is a section of Fig. 3 on the line $x^3\bar{x}^3$; Fig. 8 is a section of Fig. 1 on the dotted line $x^4\bar{x}^4$; Fig. 9, a detail showing the slotted slide-bar; and Fig. 10 shows a button-hole slit with the body-threads of the bar laid at right angles to the length of the slit and with one end thereof covered or crossed transversely by lateral stitches of the same thread.

The frame-work A, main horizontal shaft A', gears A² A³, upright shaft A⁴, crank A⁵, shuttle-carrier A⁶, link A⁷, needle-bar A⁸, needle A⁹ are all as common in the Singer sewing-machine, which, in this instance, I have selected upon which to represent my improvement.

The shaft A⁴ is provided at its lower end with a pinion, b, which engages with a pinion, b', of the same size, the teeth of which mesh with the teeth of and drive continuously a gear, b², of twice its size. The gear b² is fast upon a short shaft, b³, extended upward through a sleeve, to be described, and above the bed-plate of the machine and the bed-plate B of the attachment, and at its upper end the said shaft is provided with a cam, b⁴, partially shown in Figs. 1 and 7, and in dotted lines, Fig. 3. The cam b⁴ enters a cam-yoke, b⁵, at the rear end of a slide-bar, b⁶. (Shown separately in Fig. 9.) This slide-bar is held down upon a forked lever, c, pivoted by screw c' to the bed B by a headed screw, b⁷, (see Fig. 1,) the shank of which latter is extended through the said bar and into the said lever, so that the slide-bar, actuated by the cam b⁴, may slide readily on the said forked lever in the direction of its length, which is also in the direction of the length of the button-hole the end of which is to be barred. The slide-bar b⁶ has two guides, one of which is the screw b⁸ referred to, and the other a block, c², (see Figs. 3 and 7,) pivoted upon the top of the shaft b³, the sides of the said block fitting closely into a longitudinal groove formed at the upper part of the yoke at the end of the said slide-bar. Each reciprocation of the slide-bar b⁶ is in a line radial with relation to the shaft b³. The pressing and feeding foot d is adjustably attached to the bar d' by suitable screws, 2 3, and the said bar is pivoted at d² upon the slide-bar b⁶, so that the said pressing and feeding foot, pref-

erably serrated at its under side and borne against the fabric or material by the spring c^3 , is moved in unison with the slide-bar, thus enabling the presser and feeding foot to move 5 the said fabric or material longitudinally with relation to the length of the button-hole slit.

The pinion b' , mounted on stud 34, has fast to it a pin-wheel or a one-toothed pinion, e , the single tooth of which intermittently engages 10 the narrow spaces 4, between pairs of teeth at the periphery of a star-wheel, e^2 , placed above the gear b^2 and connected with the lower end of sleeve e^3 , surrounding the short shaft b^3 and extended up through a hole in the bed-plate 15 of the machine, (see Fig. 7,) and through the bed B of the attachment, where it receives upon it two disks, 5 6.

The star-wheel e^2 is rotated once to each eighteen rotations of the pin-wheel e , and 20 moves only while the single tooth of the pin-wheel is in engagement with the pairs of teeth of the said star-wheel, the latter remaining at rest as long as the circular hub or untoothed part of the pin-wheel (shown partially in dotted lines, Fig. 4) acts in the spaces 5 of the star-wheel between the pairs of teeth.

Instead of the pin and star wheel herein shown, any other usual form of gear may be employed to produce an intermitting movement.

The disk 5 has two throw-points, 9 10, (see Fig. 3,) and at each side of the throw-point 9 is a depression, the center of the depression and the extremity of the point 9 occupying a 35 portion of the circumference of the disk equal to the distance traversed by the star-wheel to each step or movement. The periphery of the disk 6 at the opposite side of the shaft b^3 has also two high points, 12 13, the latter being shown in dotted lines, Fig. 3, and at each side of the high point 12 is a depression, the depression between the high points 12 and 13 of the disk 6 being diametrically opposite the high point 9 of disk 5, so that the said high 40 points and depressions co-operate upon the inwardly-extended toes of the forked lever c referred to, and cause the said lever to be moved positively and quickly in each direction of its movement and for the whole distance of the 45 throw which can be given to the said lever, and the said lever is held at the extremes of its movements. As herein shown, the high points and depressions at the peripheries of the said disks are only sufficient to effect three full vibrations of the said fixed lever about its center c' , such vibrations (the pressing and feeding foot d being pressed down upon the fabric or material placed under it) causing the said fabric or material to be moved horizontally in the 50 direction of the width of the button-hole slit therein which is to be barred at its square end, so that the stitching parts produce three stitches, and cause the needle-thread to be laid on the surface of the fabric or material as 55 three long stitches, as in diagram, Fig. 10, the said stitches extending substantially from outer edge to outer edge of the stitching about the

sides of the button-hole slit. These long stitches constitute the body for the "bar," and they are subsequently overstitched transversely, or covered by the needle-thread, while the slide-bar and its attached pressing and feeding foot are being moved to move the fabric or material longitudinally, or in the direction of the length of the button-hole slit by 70 the cam b' , before described.

While the body-stitches are being covered transversely the toes of the forked lever rest upon the smooth peripheries of the disks 5 6, which are of scroll shape, or which start from 80 the extremity of one of the high points, and terminate at the base or lowest portion of one of the depressions, such scroll shape of the said disks effecting gradually a lateral movement of the fabric or material, or a slow movement at right angles to the length of the button-hole slit while the body-threads are being covered or crossed over transversely by the needle-thread, as described.

The base B of the attachment has two bearings, 14 15, to receive a rock-shaft, h , having two arms, h^1 h^2 , and a toe, h^3 , the latter being made adjustable thereon by a set-screw, h^4 , and having a pin, 16, (see Fig. 6,) adapted to ride upon the face of the disk 6, and when opposite the 90 depression 8 therein to enter the said depression and permit the rock-shaft under the action of spring 17 to be turned in the direction of the arrow 18, (see Fig. 8,) and place the dog h^5 in position to be struck by the stop-piece 20, 95 made as an arm loosely mounted upon the shaft A' , (see Fig. 8,) and located in a notch, 21, in the face and periphery of the clutch-pulley part m , and one side of the band-pulley or sheave m' loose on the shaft A' . The stop-piece 20 is backed up in a yielding manner by a spring, 22, on a curved bail-piece, 23, extended through a guide, 24, fast to the part m . One side of the said stop-piece (see Fig. 1) is acted upon by a spring-pressed pin, 30, 100 which normally keeps the stop-piece pressed toward the loose pulley m' . The loose pulley or sheave m' at its inner side is cut away, as shown at 32, forming a space to receive a nearly diametrically placed spring-arm, m^2 , 105 (shown mostly in dotted lines, Fig. 8, and also shown in end view of Fig. 1,) attached by the screw 33. (Shown in dotted lines in Fig. 1.)

When the sheave or pulley m' is being rotated in the direction of the arrow 25, Fig. 8, 110 the free end of the spring m^2 bears against the shoulder 28 of the stop-piece 20, as shown in Fig. 1, and causes the latter, by its action against the shoulder 36 of the fast pulley m , (see Figs. 1 and 8,) to drive the latter and the 115 shaft A' ; but as soon as the pin 16, before described, enters the depression 8 of the disk 6, the dog h^5 , then moved as described, enters the space 29 at the end of the stop-piece 20, 120 acting against the front of the shoulder 28, 125 forces the stop-piece back laterally in the direction of the arrow 31, Fig. 1, moving the shoulder 28 laterally away from the loose pulley m' and out of engagement from the spring 130

m^2 , referred to, which permits the pulley m' to run loose on the shaft A' , thus leaving the said shaft and the clutch-pulley part m at rest. The stop-piece 20, striking the dog h^5 , is arrested in its movement, but the fixed part m is not stopped instantly, for that would produce a disastrous shock, so to provide for that the spring 22 yields to the momentum of the part m , and gradually brings it to rest.

10 The opening 8 in the disk 6 is so located that the pin 16 enters it just before the high points and depressions of the disks 5 and 6 arrive into position to vibrate the forked lever c to effect the laying of the body-threads referred to, so that the mechanism is automatically stopped at the completion of a bar, and a second bar cannot be commenced without hand manipulation on the part of the operator, as will now be described.

15 The arm h^2 of the rock-shaft h is placed to be acted upon by a finger, 33, of a lever, n , and when the operator, the fabric having been put in place under the pressing and feeding foot d , desires to start the machine the lever n is turned to act upon the arm h^2 , turn the rock-shaft in the direction to remove the dog h^5 from its engagement with the stop-piece 20, and at the same time the pin 35, extending beneath the pivoted bar or lever d' , is lowered, 25 permitting the spring c^5 to depress the pressing and feeding foot upon the material.

20 As soon as the stop-piece is released, it is thrown forward by the spring 22, and resumes its normal position nearest the pulley or sheave m' , so that the spring m^2 on the latter, during the rotation of the said pulley, again acts upon the said stop-piece and starts the machine.

25 To lift the presser-foot for the insertion of the work it is only necessary to turn the lifting-lever n toward the needle-bar. The pin 35, which lifts the presser, and the pin 33 which turns the rock-shaft to start the machine, are at opposite sides of the fulcrum t of the said lever, the said fulcrum being shown by dotted lines 40 in Fig. 1.

30 At the top of the head of the machine near the needle-bar A^8 (see Figs. 1 and 2) I have placed a spring or nipping tension device composed of a standard or bar, 42, and a spring, 40, between which the needle-thread passes on its way to the needle, the spring acting as a tension device; but to release the thread when the needle-bar is elevated, and the needle out of the fabric, and the stitch finished only at 45 which time the work is to be removed from the machine, I have provided the spring 40 with a toe, 41, extended laterally through a hole in a standard or bar, 42, and the upper end of the needle-bar as it strikes the toe, near the 50 termination of each ascent of the needle-bar, forces the spring 40 away from the standard 42, (see dotted lines, Fig. 2,) and thus effects the release of the needle-thread, thereby leaving the latter free to be drawn through the 55 tension device for the removal of the work.

60 The opening and depression 8 at the upper

side of the disk 6 acts as a pattern or surface to determine the stopping of the machine.

The end of the button-hole to be barred is placed beneath the feeding presser foot d with 70 the button-hole lengthwise of the machine or in the line of the direction of the reciprocating movements of the slide-bar b^6 . The parts being in the position indicated by Fig. 3, and the machine being started, the points and depressions of the disks 5 and 6 will give three quick vibrations to the lever c and to the bar or lever d' and feeding-foot d carried thereby. The said feeding-foot will also be reciprocated in the direction of the length of the button-hole by the cam b^4 , to make the short barring-stitches, said foot being meanwhile moved slowly transversely of the button-hole by the scroll-shaped edges of the disks 5 and 6 to effect the proper spacing of the said 85 stitches. When the depression of the disk 6 comes beneath the toe of the rock-shaft h , (at which time the bar of the button-hole is completed,) the machine is automatically stopped by the unclutching of the driving pulley, as 90 has been described.

I claim—

1. In an attachment for barring the ends of button-holes, a yielding pressing and feeding foot to bear upon the material, a slide-bar connected with said foot and provided with a yoke, a lever by which the said slide-bar is carried and on which it can slide, a cam rotating in said yoke and serving to reciprocate the said slide-bar lengthwise, and two rotating disks having at certain portions of their peripheries oppositely-arranged projections and depressions, substantially as set forth.

2. The combination, with the base B of the attachment, of the rotating shaft b^3 , its cam b^4 , 105 the slide-bar b^6 , having a yoke, b^5 , in which said cam rotates, and the pressing and feeding foot d , connected with said slide-bar, substantially as set forth.

3. The base B of the attachment, the shaft b^3 , its cam b^4 , means to turn the said shaft, the slide-bar b^6 , having a yoke, b^5 , in which said cam rotates, and the yielding pressing and feeding foot operatively connected with said slide-bar, combined with two disks having circumferential projections and depressions, and the pivoted lever upon which said slide-bar is held and guided, said lever being forked to embrace said disks, substantially as set forth.

4. In a sewing-machine attachment, the upright shaft A^4 , pinion b , the gear b^2 , intermediate b' , shaft b^3 , its cam, the slide-bar, and the pressing and feeding foot operated by it, combined with the two disks 5 6, provided with suitable projections and depressions and with means to operate the said disks intermittently, and with the forked lever c , operated thereby, all substantially as described.

5. In a sewing-machine, a barring attachment comprising a feeding presser-foot, a rotating cam for reciprocating said foot lengthwise of the button-hole, and rotating disks

having oppositely arranged projections and depressions and scroll-shaped edges, as described, combined with a clutch-pulley and intermediate devices for effecting the stoppage 5 of the machine when the bar is completed, substantially as set forth.

6. The feeding-foot, the slide-bar, the pivoted forked lever to carry the latter, combined with the rotating disks 5 and 6, embraced by the fork of said lever, and having circumferential projections and depressions to move the said lever quickly over the greatest distance traveled by it to effect the movements of the said foot crosswise of the button-hole, and having other circumferential portions scroll-shaped, as described, to move said lever slowly from one to its other position, combined with a rotating cam to reciprocate the said slide-bar and foot in the direction of the length of the button-hole slit, substantially as and for the purpose set forth.

7. The combination, with the feeding presser-foot *d* and its operating mechanism, including the disk 6, having the depression 8, of the

rock-shaft *h*, having a toe provided with a pin 25 adapted to engage said depression, and having also an arm carrying a dog, of a clutch-pulley adapted to be unclutched by said dog when the said pin is forced into said depression, substantially as set forth.

8. The combination, with the reciprocating needle-bar, of the post 42, secured to the sewing-machine head or face-plate adjacent to said bar, and having a flattened face and a tension-spring, 40, pressing against said flattened face, and provided with a projection, 41, extending beyond said post into the path of the needle-bar whereby said spring will be forced away from said post at the upward movement of the needle-bar to release the thread, substantially as set forth.

In testimony whereof I have signed my name to this specification in the presence of two subscribing witnesses.
